SOLE ROUGHING MACHINE

Elzear J. Le Gault, Haverhill, Mass., assignor, by direct and mesne assignments, to Bestco Shoe Machinery Inc., Ipswich, Mass., a corporation of Massachusetts

Application September 2, 1937, Serial No. 162,077

5 Claims. (Cl. 69—1)

My invention relates to machines for roughing soles used in the manufacture of shoes by the so-called cement process. In the latter process, the inner marginal surface of the sole is cemented to the overlasted margin of the upper. It has long been realized that cement will not form a secure and permanent bond with leather unless the leather is first treated to disrupt the smoothness or glaze of its surface and raise small fibres around which the cement can flow. Such a result can be obtained by abrading the sole with a radial wire brush, but the machines heretofore available have proved unsatisfactory because their operation is too slow, and there is considerable likelihood of painful injuries to the operator resulting from the necessity of pushing the sole through the machine and the consequent danger of touching the rapidly revolving wire brush.

An object of my invention is to provide improved means for feeding a sole automatically through the roughing machine so that the operator need not touch it except to place it in the starting position and remove it after roughing has been completed. As herein shown, the desired results are accomplished by the combination with a roughing roll and feed roll arranged to rotate about parallel horizontal axes and to cooperate in advancing the sole between them, of gauge rolls so located as to engage the margin of a sole in a line oblique to the axes of said rolls.

An important feature of my invention consists in a novel assembly of a work table and feed roll whereby variations in the thickness of the soles being treated are compensated for.

A further feature of my invention comprises a roughing-roll shaft adapted to drive a feed roll shaft at considerably less speed than the roughing-roll shaft and including a novel connection between the feed roll and the roughing-roll shaft permitting variation in the location of these two members without interrupting the driving operation.

These and other features of my invention will be best understood and appreciated from the following description of a preferred embodiment thereof selected for purposes of illustration and shown in the accompanying drawings, in which:

Fig. 1 is a view in side elevation of the machine with some parts removed for purposes of clarity,

Fig. 2 is a view in perspective of one end of the machine; and

Fig. 3 is a plan view showing the relation of the gauge rolls to the feed roll.

Bolted to the hollow base 10 is an upright,

rectangular gear housing 11 having an overhanging, hollow, horizontal arm 12 bolted to one side of its upper portion. A shaft 13 is journaled in the housing 11 and in the outer end of the horizontal arm 12 and is protected by a sheet metal cover 14 secured by screws 42 to the side of the arm. The shaft 13 carries at its outer end a roughing roll 15 which is held against longitudinal movement by a shoulder and a nut 16 threaded on the shaft 13. The roughing roll 15 herein shown consists of wires set radially in a central hub, a construction well known in the art. Cut in the shaft 13 at a point within the gear housing 11 are gear teeth forming an elongated pinion 17 which meshes with a spur gear 18 keyed on the shaft 19 journaled horizontally within the housing 11. A gear 20 also keyed on the shaft 19 is much smaller in diameter than the gear 18 and meshes with a pinion 21 splined to a horizontal shaft 22 which is journaled in the housing 11. A shaft 24 is disposed near the bottom of the housing 11 and carries a large gear 23 which is arranged to mesh with the pinion 21. One end of the lower shaft 24 extends through the side wall of the housing 11 and terminates in a fork 25 forming one element of a universal joint with a similar fork integral with a spindle 26. The opposite end 28 of the spindle 26 which is tapered enters a hole in an inclined and angularly movable shaft 29. A groove and key connection between the inclining shaft 29 and the end 28 of the spindle prevents relative rotation of the spindle 26 and the shaft 29, although longitudinal movement is permitted. At the upper end of the inclined shaft 29 is a universal joint formed in part by a fork 30 integral with the rod 29 and a similar fork 31 on the end of a horizontal shaft 32 which is journaled in a yoke 33 bolted to a flat circular work table 35 by bolts 36 ground flush with the surface of the table 35. The horizontal shaft 32 carries a knurled, bevel-edge feed roll 34 partially protruding through a rectangular aperture in the work table 35. The shaft 32 is parallel to the shaft 13 and the rolls 15 and 34 rotate in the same vertical plane engaging and feeding the sole between them. The work is engaged by the rolls for feeding along a transverse line located midway between the ends of the exposed segment and the lower feed roll 34. The rolls tend to feed the work in the direction of the arrow shown in Fig. 3, but the work is prevented from moving as a whole in that direction by gauge rolls.

Referring again to Fig. 3, it will be seen that a pair of gauge rolls 37 and 38 freely rotating on

vertical axes are disposed on a line oblique to the axes of rotation of the feed rolls. The gauge rolls 37 and 38 are located one on each side of the feed roll 34 with the outer roll 37 the furthest away from the line of feeding engagement. The periphery of the feed roll 34 tapers or converges outwardly from the inside edge of the roll.

Integral with the yoke 33 is a downwardly extending threaded spindle 39 upon which a threaded stem or regulator disc 40 is carried. Surrounding the portion of the spindle 39 below the disc 40 is a helical compression spring 41 resting in a socket 43 in the hollow base 10. By rotating the regulator disc 40 the spindle 39, with the yoke 33 and the circular work table 35 carried thereby, is raised or lowered and thus adjusted with respect to the roughing roll 15 without varying the compression of the spring 41. The circular work table 35 is provided with an angular recess 44, the edges of which embrace the housing 11 and prevent lateral movement of the table 35 while allowing vertical movement thereof. It will be seen that the universal joints connecting the shaft 24 to the shaft 32 permit vertical movement of the latter shaft without interrupting the rotational actuation thereof.

A pulley 45 keyed on the rear end of the horizontal shaft 13 is belted to any suitable source of power. By experimentation, I have discovered that the most efficient operation of the machine is obtained when the roughing roll 15 turns at 2,100 R. P. M. and the rate of the feed roll 34 is 160 R. P. M., a ratio of approximately 13:1. The train of gears in the housing 11 reduces the speed of 2,100 R. P. M. at the pinion 17 to 160 R. P. M. at the shaft 24. When higher speeds are used, the soles are likely to be jerked through the machine and portions of the margins are not roughened. Lower speeds are unsatisfactory because production is retarded.

In operating the machine, the operator places one edge of the sole between the roughing roll 15 and the feed roll 34, after having manipulated the regulator disc 40 to obtain proper clearance between the two rolls. Both rolls urge the sole forward as shown in Fig. 2, but the slower moving feed roll 24 retards the progress of the sole so the roughing roll 15 will act as an abrading means and not solely as a feed roll. In other words, each point on the under side of the sole has contact with but one point on the feed roll 34, while each corresponding point on the upper margin of the sole is subjected to the abrading action of a section of the roughing roll 15.

The sole, as explained, is urged forward by the two driven rolls but is deflected from the feeding line of these rolls by the gauge rolls 38 and 37 aided by the taper of the feed roll 34. In other words, the forward force exerted on the sole by the driven rolls is resolved into two forces by the action of the gauge rolls, one tending to press the edge of the sole against the gauge rolls and the other tending to advance the sole obliquely in a line parallel to the gauge rolls. The resultant movement causes the edge of the sole to travel against the gauge rolls, the rolls automatically following every curve in the edge of the sole and the sole turning and twisting into continuous contact with the gauge rolls so long as it is left in the machine. However, the usual roughing is confined to the forward portion of the shoe from breast line to breast line, and the

operator may remove the sole at any desired moment in its course.

While manipulation of the regulator disc varies the distance between the roughing roll 15 and the feed roll 34 in accordance with the will of the operator in view of the average thickness of the soles to be run through, the spring mounting of the spindle 39 takes care of variations in the thickness of the individual soles as they are put through the machine.

Having thus disclosed my invention, I claim as new and desire to secure by Letters Patent:

1. A sole roughing machine comprising a sole support, a roughing roll and feed roll arranged to rotate about parallel, horizontal axes and to cooperate in advancing the sole between them, and gauge rolls so located as to engage the margin of a sole in a line oblique to the axes of said rolls.

2. A sole roughing machine comprising a work table having an aperture, a roughing roll disposed for rotation over said aperture, a yoke secured to the underside of said work table and embracing said aperture, a shaft journaled in said yoke, a feed roll keyed on said shaft and partially extending through said aperture, a spindle integral with said yoke and projecting downwardly, a spring supporting said spindle, and means for adjustably controlling the height of said work table and feed roll.

3. A sole roughing machine comprising an apertured work table, a roughing roll disposed for rotation over said aperture, a yoke secured to said work table and embracing the aperture in said work table, a shaft journaled in said yoke, a feed roll keyed on said shaft and partially extending through said aperture, a spring supporting said spindle, a housing extending above the plane of the work table, a horizontal shaft extending through said housing and carrying said roughing roll, a gear shaft journaled in said housing, an inclined angularly movable shaft connecting the shaft in said yoke to said gear shaft, and a gear train between said horizontal shaft and said gear shaft, said gear train being constructed and arranged to turn said gear shaft more slowly than said horizontal shaft.

4. A sole roughing machine having a frame, a rotary roughing tool mounted therein, and a flat work table for supporting a sole beneath the roughing tool, the table being carried by a yoke which has its stem guided for vertical movement in the frame, a feed roll journaled in the yoke and projecting through the table a fixed distance, means for adjusting the table, yoke and feed roll as a unit toward or from the roughing tool, and means for yieldingly supporting said unit in different positions of adjustment.

5. A sole roughing machine having a frame with an upstanding portion, a rotary roughing tool mounted therein, and a flat work table for a sole being roughed, the table being carried by a yoke which is slidably retained in the frame and being held against angular displacement by engagement with the upstanding portion of the frame, a feed roll journaled in the yoke and extending up through the table, a disk on the stem of the yoke, and a spring beneath the disk yieldingly supporting the table, yoke and feed roll as a unit.

ELZEAR J. LE GAULT.
